United States Patent Office

Des. 195,383
Patented June 4, 1963

195,383

PASSENGER AIRCRAFT

Lawrence B. Rellis, Chicago, Ill.
(9241 N. Olcott, Morton Grove, Ill.)

Filed Apr. 2, 1962, Ser. No. 69,523

Term of patent 14 years

(Cl. D71—1)

Des. 195,383

PAGE 2

FIG. 1 is a top plan view of a passenger aircraft, showing my new design;

FIG. 2 is a bottom plan view thereof;

FIG. 3 is a side elevational view thereof, in landing position;

FIG. 4 is a front elevational view thereof;

FIG. 5 is a rear elevational view thereof; and

FIG. 6 is a side perspective view thereof.

I claim:

The ornamental design for a passenger aircraft, as shown and described.
